SLEEVE PRESS OPERATING MEANS

Louis N. Strike, Salt Lake City, Utah, assignor, by mesne assignments, to The American Laundry Machinery Company, a corporation of Ohio

Application January 3, 1956, Serial No. 557,036

11 Claims. (Cl. 223—73)

This invention relates to means for operating a sleeve press to so relatively adjust the press that sleeves of a garment draped on the press are properly ironed.

Since sleeve lengths vary in a run of shirts being successively handled by a sleeve-pressing machine, operator-controlled means are provided to effect relative adjustment of pressing plates or platens and sleeve-draped bucks. Such adjustment is made to insure that the entire length of the sleeves, regardless of length variations, is ironed, yet not subjecting any adjacent parts of the shirt body to the ironing pressure of the pressing platens. Ideally the seams connecting the sleeves to the body constitute the limits of engagement of the platens. Accordingly, it is an object of the present invention to provide novel and improved means enabling the operator to set the press quickly and easily according to the length of the sleeves mounted thereon.

Another object of the invention is to provide operator-controlled mechanism of the character above referred to that sequentially carries out first, the mentioned relative adjustment of the sleeve-draped bucks and the pressing platens and, then, the operative movement of the bucks and platens between draping or dressing and pressing positions.

The present sleeve press is an improvement of the pressing machine disclosed in Serial No. 369,915, filed July 23, 1953, now U. S. Letters Patent No. 2,727,661. In the machine there disclosed, the pressing platens are shifted endwise by the operator through the medium of linkage connecting the platens and an operating handle. Thus, there is a direct connection between the operating handle and the pressing platens that causes simultaneous movement of handle and platens. Also, the handle shown by said patent must be held steady during movement of the sleeve-draped bucks from the dressing to pressing position to insure that the adjusted relationship is maintained.

Therefore, another object of the present invention is to ease and simplify the adjusting operation so that the handle, rather than operating the adjusting means, may be moved to sleeve and seam-aligning position and, therefore, constitute means for setting or limiting the adjusting movement of the platens.

A further object of the invention is to provide platen movement-limiting means that is held in a set position by power means rather than by the operator, and which constitutes an accurate stop for the platens when thus held in its set position.

A still further object of the invention is to provide mechanism of the character referred to that automatically releases itself from its set position after performing a pressing operation, thus insuring against repetition of the operation unless the handle is re-set by the operator. The invention also has for its objects to provide such means that are positive in operation, convenient in use, easily installed in a working position and easily discon-

nected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

10 In the drawings, like reference characters designate similar parts in the several views.

Fig. 1 is a side elevational view of a sleeve press embodying the present operating means, the same being shown with portions of the side housing broken away to expose the mechanism, the press being shown in dressing position.

Fig. 2 is a schematic view of the elements of the machine that are essential to the present invention and the manner of their operative interconnection.

20 Fig. 3 is an enlarged and broken plan view of the operator control means shown in the right upper portion of Fig. 2.

Fig. 4 is a similarly enlarged sectional view of the handle-braking means shown in Fig. 2, said view being taken on the line 4—4 of said figure.

Fig. 5 is a plan view of the means shown in Fig. 4.

The sleeve press partially shown in Fig. 1, and more completely shown in the mentioned patent, comprises a cabinet-like frame 10 that has side walls 11 which mount guide rods 12 by means of brackets 13 affixed to said walls. A carriage 14 is guided for movement along said rods by engagement of tracking rollers 15 with said rods. Since said rods 12 are preferably disposed at a rearward and upward angle, the carriage 14 is movable, accordingly.

Said carriage mounts pressing platen means 16 which may comprise two pairs of hingedly-connected pressing platens 17, each said pair being carried by a pair of arms 18 mounted on the carriage. While the details of construction of the platen means 16 are not shown, since the same is not a feature of the present invention, it will be understood that the arms 18 are hingedly connected to the carriage so that fluid-operated piston-cylinder units 19, together with suitable spring means 20 may move the platens between open and closed positions by causing appropriate hinging movement of arms 18. Since the carriage 14, together with the platen means 16, gravitationally, seek a low position on the rods 12, against the counter-balancing bias of spring 21, a fluid-operated piston-cylinder unit or units 22 may be used to raise the carriage and thereby shift the platens upwardly along rods 12. A buffer spring or springs 23 may be used for absorbing any shocks attending lowering of the means 16 after its release from a raised position. It is the lower edge 24 of the platens 17 that is the variable that limits engagement of the platens.

The press includes buck means 25 that may comprise a tray 26 for supporting a shirt body, and a pair of bucks 27 extending upward from the tray and transversely spaced thereon so that said pair of bucks can operatively engage the pairs of platens 17, as will be described below. Each buck may be provided at its upper end with a cuff clamp 28, and with an expander 29, that, after the sleeves are draped on the bucks, may be laterally outwardly projected to effect tautening of the sleeves preparatory to pressing.

The buck means 25 may be carried on a pivot 30 by means of arms 31 extending between said pivot and the tray 26. The pivot 30 is so located in the frame 10 that the buck means 25 may assume a dressing position (Fig. 1) slightly forward of an erect position and, when rear-

wardly tilted, a position with the bucks 27 between the pairs of pressing platens.

A bracket 32 on frame 10 mounts a fluid-operated piston-cylinder unit 33 which is extensible to effect movement of the buck means on its pivot toward the pressing platens, said unit 33 having a connection 34 with the arms 31. Spring means 35 effects a return movement of the buck means 25 from the pressing position to the dressing position shown in Fig. 1.

The foregoing generally describes a sleeve press adapted to be provided with the hereinafter described operating means, it being understood that either the platens or the bucks may be longitudinally adjusted, since it is necessary only to effect relative adjustment of such members. Also, either the platens or the bucks may be moved to pressing position. In other words, the bucks and platens comprise cooperative pressing members, one of which is longitudinally adjustable and one of which is movable into and out of pressing position.

Such a machine may also include means 36 for operating the expander 29 through the medium of a pedal 37.

According to the present invention, the control means for a sleeve press of the type above described comprises, generally, setting means 40 adapted to be manually set in position to align with and, therefore, assume an adjusted position in relation to one shoulder-sleeve seam of a pair of sleeves draped on the bucks 27, operator-controlled locking means 41 to simultaneously operate the mentioned unit 22 to effect adjusting movement of the carriage 14 and platens 17 carried thereby and operate brake means 42 to lock the adjusted position of the means 40, means 43 affixed to and movable with the carriage 14 and extending into operative engagement with the setting means 40, cooperative stop means 44 mounted in part on the means 40 and in part on the means 43 to actuate a control-valve assembly 45 and operate the piston-cylinder unit 33, control valve means 46 controlled by said unit 33 to operate the piston-cylinder units 19, and releasing means 47, carried by the means 40, controlled by one of said units 19 to operatively release the stop means 44 and brake means 42.

The manually settable means 40 comprises an arm 50 mounted on a pivot 51 on one of the frame sides 11. The free end of said arm is provided with a handle 52 and the arm is so directed that said handle extends forwardly in ready position to be grasped by the press operator. A spring 53 is provided for biasing the arm in an upward direction so that the portion of the arm that is adjacent the handle is opposite one of the bucks 27 and when the arm is moved on its pivot, said handle portion has movement generally longitudinal with respect to the buck length.

The portion of the buck opposite which said arm portion moves is that portion at which a shoulder-sleeve seam of a sleeve draped on the buck is disposed. Since shirt sleeves do not vary more than three or four inches, and the location of the sleeve cuff is constant as determined by the cuff clamp 28, the longitudinal position of the mentioned seam will vary accordingly. The range of pivotal movement of arm 50 is arranged to span the different seam positions.

The setting means 40 further comprises a light unit 54 that is mounted on the mentioned arm 50 in position to direct a beam of light against that portion of the buck 27 opposite which the arm is set. While the electrical details of light unit 54 are not illustrated, it will be understood that said unit may contain a suitable lamp bulb in housing 55 and electrical connections therefor, and that the light from said bulb may be directed by a lens 56 toward the buck as a spot of light. Since most shirts are white, said lens may be colored red, for instance, to provide a red spot on the shirt sleeve seam or adjacent thereto.

Accuracy of arm adjustment relative to the sleeve seam may be provided by mounting housing 55 for adjustment

relative to arm 50. Such adjustable mounting means is indicated by the stud 57, carried by said arm, and a slot 58 through which said stud extends and which is provided in an extension 59 of housing 55.

The locking means 41 is shown as pneumatically operated, the present control means, generally, being so operated. It will be understood, however, that pneumatic operation, while preferred, is intended as exemplary. As shown, the means 41 comprises a valve 60 mounted by means of a bracket 61 on arm 50. Said valve has an air inlet connection 62 and an air outlet connection 63 that are normally maintained out of communication by a piston on the end of stem 64. A finger plate 65, pivotally mounted on said arm 50, is engaged with said stem and so directed that a finger of the hand grasping handle 52 may depress said plate to cause actuation of valve 60 and communicate the pressure in connection 62 to connection 63. This valve 60 is opened after the operator has set the means 40 so that the beam of light is directed as desired and while the operator holds the handle 52 of said setting means 40.

The air in connection 63 is directed to a unit 66 in which is housed a diaphragm 67 and a stem 68 that is projected by said diaphragm when impinged by air from connection 63. Said stem 68 controls a valve 69 that is similar to valve 60, the control being effected through the medium of a control toggle 70. A common bracket 71 may mount diaphragm unit 66, valve 69 and toggle 70. Valve 69 is normally closed and has an air inlet connection 72 which may be connected to the same source as connection 62, and an air outlet connection 73 that is connected to both the unit 22 and the brake means 42 to operate said unit and means simultaneously.

Since the carriage 14 is normally in its lowermost position, as above explained and the unit 22 is normally not under pressure, the air from connection 73 will extend the piston rod 74 of said unit and, by means of connection of said rod and carriage 14, the latter and the pressing platens 17 mounted thereon will be raised.

The brake means 42 is shown in detail in Figs. 4 and 5, said means comprising a fixed brake plate 75 carried by one frame side 11 as by studs 76, a parallel brake plate 77 slidably mounted on said studs and carrying opposed adjustable limit screws 78, a pair of diaphragm units 79 mounted on frame side 11 and provided with projectable stems 80 in impingement with the movable brake plate 77, and springs 81 on studs 76 biasing the plate 77 in a direction opposite to the direction of movement caused by stems 80.

Connection 73 is made to fittings 82 on the units 79. Therefore, the pressure controlled by valve 69 will actuate the diaphragms 83 of units 79, project stems 80, and cause firm gripping of arm 50 between plates 75 and 77. Since valve 69 is of the self-exhausting type when unactuated, connection 73 exhausts through said valve when toggle 70 is broken, releasing arm 50 as springs 81 cause separation of the braking plates. The arm will then return to its most elevated position under influence of spring 53.

It will be seen from the foregoing that immediately upon finger-actuation of the finger plate handle 65, the means 50 is engaged by the brake means so that handle 52 may be released by the operator. Since self-exhausting valve 60 will now be released to return to closed position, connection 63 will exhaust and allow retraction of stem 68 of diaphragm unit 66. However, toggle 70 will remain broken and valve 69 open until over-center tripping of spring 84 of said toggle occurs.

The means 43 is shown as an elongated member 85 that is affixed to carriage 14 and, therefore, moves therewith. At its lower end, said member 85 is provided with a forward extension 86 that, in the lowermost position of said carriage, extends above the tray 26 and terminates at its forward end forward of the machine frame and opposite to the buck 27 that is most adjacent. Since

extension 86 moves in a path guided by carriage guide bars 12, the same moves toward arm 50 in an upwardly and rearwardly angled path.

The stop means 44 is, in part, carried by the arm 50 and, in part, by extension 86. The portion of said means 44 that is carried by arm 50 comprises a valve actuator 87 that is carried by said arm on a pivot 88. Said actuator 87 extends laterally from arm 50 in overstanding relation with the end of extension 86. A spring 89 is connected to an extension arm 90 of the actuator, said extension arm being directed from pivot 88 opposite to the direction of extent of the actuator. Said spring biases the actuator to the lateral full-line position shown in Fig. 3.

The portion of means 44 that is carried by extension 86 comprises a valve 91 that has an operating end 92 and is affixed to the end of said extension by a bracket 93. Said valve is similar to valves 60 and 69 in construction and has an air inlet 94 and an outlet connection 95. Said end 92 is so located with respect to actuator 87, that the same is engaged and depressed by said actuator to open the valve when the rod 74 of unit 22 is extended by air in connection 73. Although there are some differences in the position of the actuator, as caused by the adjustment of arm 50, the valve end 92 may be located to insure engagement with the actuator during all positions of adjustment of arm 50.

Since arm 50 of the setting means 40 is firmly braked against movement, the upward movement of extension 86 and, consequently, carriage 14 and platens 17 will be arrested when valve 91 has been opened. Thus, the pressing platens 17 will assume an elevated position that corresponds to the adjusted position of means 40. The more elevated the means 40 and the actuator 87, the more elevated will be the corresponding position of the platens.

The control valve assembly 45 comprises a diaphragm unit 96 that receives the pressure in connection 95, said unit having a stem 97 that projects in response to such pressure. A toggle device 98 is actuated by said stem to move arm 99, the latter being engaged by a stem 100 of a valve 101. Said valve has an inlet connection 102 that supplies outlet connections 103 and 104 when the toggle 98 is moved to over-center position by stem 97 as shown in Fig. 2 by the dot-dash lines. The valve stem 100 is spring-biased, as shown, to project and close valve 101 except when retracted by the toggle.

The control valve assembly 45 includes a diaphragm unit 105 that has a stem 106. Projection of stem 106 breaks toggle, such projection being caused by air pressure in a connection 107.

A timer unit 108 is provided for timing the actuation of diaphragm unit 105, the same controlling a valve 109 which has an air inlet connection 110 and the connection 107 as its outlet. The timer unit 108 is merely typical of any means that may be provided for causing actuation of diaphragm unit 105 at a desired time.

Connection 103 is connected by a fitting 111 to one end of cylinder 112 of the piston-cylinder unit 33 that causes movement of the buck means 25 from dressing to pressing position. The piston stem 113 of unit 33 is projected by such pressure acting on the piston of said stem. As can be seen from Fig. 1, such projection of stem 113 will cause the mentioned pivotal movement of the buck means to pressing position.

The cylinder 112 is provided with a fitting 114 that is opened to the pressure supplied by connection 103 when the buck means has reached pressing position. Therefore, pressure from said cylinder enters a connection 115.

The control valve means 46 comprises a valve 116 that has connection 104 as its air inlet and is provided with an outlet 117 that includes two branches 118. The connection 115 controls a diaphragm unit 119 which causes actuation, or opening, of valve 116 when the port of fitting 114 is uncovered. Since said branches 118 are then under air pressure from connection 104, and are connected to the

piston-cylinder units 19, the arms 18 are actuated to cause the pressing platens 17 to close over the sleeve-draped bucks. The pressing time is controlled by the mentioned timer 108, since the same causes closing of valve 101 and exhaust of connections 103 and 104 through the vent or exhaust provided in said valve.

As the pistons 120 of units 19 are projected to close the pressing platens, the piston 121 on one of said units exposes a connection 122 that is provided with a valve 123 that can be set to restrict the flow in said connection, as desired. This restricted flow is used to operate the releasing means 47 to cause the actuator 87 to release the valve end 92. Thus, valve 91 is exhausted, and the platens 17 are held in position by the pressure in connection 73 only.

The means 47 is shown as a fixed bracket 124 on arm 50, a cylinder 125 carried by a pivot 126 on said bracket, a piston 127 in said cylinder, and a piston stem 128 on said piston and directed to bear against extension arm 90 of the actuator 87. Said actuator and cylinder move pivotally in the same plane, as can be seen best from Fig. 3. The connection 122 supplies air to cylinder 125 as controlled by restriction 123. In this way the operator can control the operation of the release means 47.

When stem 128 is projected, it causes the actuator 87 to swing to the dot-dash line position of Fig. 3 and, thereby, releasing valve end 92, causing the normally closed valve 91 to close and vent, and exhausting the pressure in diaphragm unit 96. Now, when the timer 108 re-sets 30 toggle 98, to close valve 101, reactivation of said valve by the toggle is prevented since stem 97 may yield to the toggle movement.

After valve 101 is closed, and when connection 103 and unit 33 are exhausted, the spring means 35 (Fig. 1) will 35 return the buck means 25 to dressing position. At this time units 19 will have been rapidly exhausted through valves 101 and 116 to allow the springs 20 to open the platens 17. This movement of the buck means is used to trip spring or springs 84, restore the toggle 76, move 40 valve 69 to closed, venting position and, thereby, exhaust the air from connection 73, unit 22 and brake means 42. Thus, the setting means 40 is free to return to its normal raised position and the carriage 14 is released to drop, while being counter-balanced by spring 21, to its normal low position.

After removal of the shirt and replacement by another, the means 40 is again set according to the length of the sleeves of the newly mounted shirt and the operation is repeated as above described.

When the actuator 87 is removed from engagement with the valve end 92, the force of pressure in unit 22 is prevented from further raising the carriage by engagement with the arm 50 of a stop 129 carried by the bracket 93 that mounts valve 91.

While the foregoing has illustrated and described what is now contemplated to be the best mode of carrying out the invention, the construction is, of course, subject to modification without departing from the spirit and scope of the invention. It is, therefore, not desired to restrict the invention to the particular form of construction illustrated and described, but to cover all modifications that may fall within the scope of the appended claims.

Having thus described my invention, what I claim and desire to secure by Letters Patent is:

1. In a sleeve press, the improvement therewith comprising setting means for a pressing member of said press, said means comprising a pivoted arm having a handle, means carried by said arm to generate a beam of light for gaging the adjusted position of the arm, and a brake for said arm to hold the same in adjusted position to enable release of the handle thereof by the operator.

2. In a sleeve press, the improvement therewith comprising setting means for a pressing member of said press, said means comprising a pivoted arm having a handle, means carried by said arm to generate a beam of light for

gaging the adjusted position of the arm, a normally-released brake for said arm to hold the same in adjusted position, when the brake is set, to enable release of the handle thereof by the operator, and means controlled by the hand on said handle to apply said brake.

3. In a sleeve press having a frame with a pair of bucks on which the sleeves of a garment are adapted to be draped, and having pressing platens for pressing sleeves draped upon said bucks, said bucks and said platens being movable toward and away from each other, and said platens being movable endwise of the bucks, the improvement therewith comprising adjustable setting means adapted to be set in a position opposite to the shoulder seam of one of said sleeves, said means being pivotally mounted on the mentioned frame, brake means also mounted on said frame and adapted to releasably hold the setting means in its adjusted position, and locking means carried by the setting means and connected with the brake means and the pressing platens to simultaneously operate said brake means and move the platens endwise of the bucks according to the adjustment of the setting means.

4. In a sleeve press according to claim 3: The locking means moving the pressing platens in a direction to be stopped by the setting means to, thereby, locate the platens endwise of the bucks according to the adjustment of the setting means.

5. In a sleeve press according to claim 3: Stop means mounted, in part on the setting means, and a unit mounted on said frame for moving the bucks and platens toward and away from each other, said unit being operated by the stop means after the mentioned movement of the platens endwise of the bucks.

6. In a sleeve press according to claim 5: Said unit also controlling the pressing movement of said platens when the bucks are in pressing position, there being a timer to control the length of time the mentioned sleeves are being pressed.

7. In a sleeve press having a pair of bucks on which sleeves of a garment are adapted to be draped and having pressing platens for pressing said sleeves, the combination comprising setting means mounted on the frame of said press, said means including a source of light for setting said means by directing a beam of light onto the shoulder seam of one of said sleeves, brake

means also mounted on said press and operatively associated with the setting means, and locking means mounted on said setting means for simultaneously operating said brake means to, thereby, hold said setting means in its set position and to institute movement of the platens in a direction toward said setting means, said platens being stopped by said setting means, and thereby, located relative to the bucks according to the adjustment of the setting means.

10. In a sleeve press according to claim 7: Said setting means including a handle, and said locking means including a finger plate, said plate and said handle being adjacent so as to be operable by the same hand of the operator.

15. In a sleeve press according to claim 7: One of the pressing platens being provided with an extension partly coextensive with the setting means, and stop means mounted, in part, on said setting means and, in part on said extension, the two parts of said stop means inter-engaging each other upon movement of said platens to control 20 the mentioned stopping of said platens according to the adjustment of the setting means.

10. In a sleeve press according to claim 7: One of the pressing platens being provided with an extension partly coextensive with the setting means, and stop means mounted, in part, on said setting means and, in part, on said extension, the two parts of said stop means inter-engaging each other upon movement of said platens to control the mentioned stopping of said platens according to the adjustment of the setting means; and means controlled by the stop means to operate said sleeve press according to the mentioned adjustment of the platens relative to the bucks.

11. In a sleeve press according to claim 10: The last mentioned means comprising a control valve assembly, and said setting means, said brake means, said locking means and said stop means all having valves and parts connected in series with each other and with said assembly, whereby the movements of said sleeve press are performed sequentially.
